METHOD AND APPARATUS FOR UNITING
WARPSRaymond Welch, Sanford, Maine, assignor to
Goodall-Sanford, Inc., Sanford, Maine, a cor-
poration of Maine

Application May 6, 1949, Serial No. 91,770

13 Claims. (Cl. 28—47)

1

When in the weaving operation the warps in a loom are exhausted or run out it is usually desirable to continue the warps, and thus the weaving operation, by uniting the ends of the running warps in the loom to the ends of a fresh set of warps, and the object of this invention is to provide a novel method and apparatus for thus uniting or continuing the warps.

The object of the invention is further to provide such a method and apparatus in which the ends of the warps are united by means of an adhesive, thus eliminating knots or other obstructions hindering the passage of the united warps through the various mechanisms of the loom.

The object of the invention is further to enable the uniting of the warp ends to be performed rapidly and efficiently and without the use of complicated or expensive apparatus.

The nature and objects of the invention will appear more fully in the accompanying drawings and will be particularly pointed out in the claims.

The drawings illustrate a simple and preferred form of apparatus embodying the invention and suitable for carrying out the method of the invention. Since the invention is applicable to looms of a wide variety of types, and since the mechanism of looms is familiar to those skilled in the art, it is only necessary to illustrate diagrammatically the elements of one type of loom in order to disclose the invention. For that purpose a loom of that type employing two warp beams, one above the other, has been selected as showing the applicability of the invention to the continuing of the warps for each beam.

It will be understood also that the mechanism illustrated for carrying out the invention in connection with the loom is also in somewhat diagrammatic form and that the proportion and arrangement of the various elements may be varied as required.

In the drawings:

Fig. 1 is a side elevation, partially broken away, showing the main elements of the loom together with a preferred form of the apparatus for uniting the warps associated therewith;

Fig. 2 is a view, partially broken away and in perspective, illustrating the principal elements of the apparatus shown in Fig. 1, and illustrating the method employed in securing the overlapping of the warp ends;

Figs. 3 and 4 are side elevations of the elements shown in Fig. 2 illustrating steps in the carrying out of the method;

2

Fig. 5 is a top plan view of the main elements of a slasher illustrating the means employed for segregating the ends of the warp of a supply beam;

Fig. 6 is a detail of a portion of one element of the divider employed in the apparatus.

The loom illustrated comprises a suitable frame 1, only a portion of which is shown, carrying at the bottom a running warp beam 2, and at the top a second running warp beam 3. The running warps lead from these beams through usual heddles 4 and beat-up reed 5 to the fell 6 of the cloth being woven. The warps 7 from the lower running beam are shown as running over a pair of rolls 8 on their way to the heddles and in the same way the warps from the upper running beam 3 are shown as running over a pair of rolls 9 and then over rolls 10 and 11 on their way to the heddles.

One feature of the invention involves the maintaining segregated with a separator of the running warps as they enter the loom from the running beam. This term "separator" is here used to indicate means which acts to maintain segregated the warps in a sheet of warps and may include more than one element. Such a separator may consist simply of a reed, similar in general to that employed on the lay, when it is practical to maintain the warps with one in each dent. Where it is desired to run two warps in each dent of a reed then such a separator may include lease rods which, together with the reed, enable the segregation of the individual warps to be maintained. In the case of the upper beam illustrated the separator is shown as comprising simply a reed 12 removably mounted on the loom frame between the rolls 9, while in the case of the lower beam 2 the separator includes a reed 13 removably mounted on the loom between the rolls 8 and a pair of lease rods 14 of the usual type.

The invention also requires that the ends of the warps on the supply beam also be maintained segregated and for that purpose another separator is employed which in turn may comprise simply a reed or a reed together with a pair of lease rods. The application of the separator to the ends of the warps on the supply beam may be effected in any suitable way, but conveniently may be done at the time the warps are passing through the slasher and wound upon the supply beam. Such an arrangement is illustrated in Fig. 5 where the fresh warps 15 are shown passing through the slasher 16 and being wound upon 50 a supply beam 17. In such a slasher the warp

ends are usually segregated by an adjustable comb, such as 18. In this case a reed 19 is removably mounted in the slasher and also when required a pair of lease rods 20 are mounted in the slasher, thus to enable the warps to be held segregated by the separator element at the conclusion of the slashing operation.

With the running warps in the loom thus maintained segregated, and with the ends of the warps on the supply beam thus maintained segregated, the apparatus further illustrated at the right of Fig. 1 and in Figs. 2, 3, and 4, is provided for securing the ends of the warps on the supply beam to the ends of the running warps in the loom so that the weaving may proceed with the warps continued.

The apparatus thus illustrated in a simple and preferred form comprises a suitable frame shown as having a base 21 mounted on rollers 22 and upright side members 23 and horizontal side members 24 and on this frame are provided supports 25 for the gudgeons 26 of the supply beam 17, while on the horizontal members 24 are removably mounted the main elements which extend transversely of the frame between the side members.

In carrying out the method of uniting the warp ends the supply beam is mounted in the gudgeon supports 25 on the supporting frame and the frame is preferably moved up to the rear of the loom so as to be closely adjacent thereto as indicated in Fig. 1.

The supporting frame at the rear end, or that toward the loom, is provided with a roller 27 extending transversely and resting in supports 28. Next, supports 29 are provided at each side for a separator reed, such as 12, of the running warp ends. Next is provided a divider carried on a support 30 extending transversely of the frame and removably mounted thereon. Next is provided another pair of supports 31 for a reed, such as 19 forming the separator for the supply warp ends. Next a roller 32 extending transversely of the frame and mounted in supports 33.

The ends of the running warps and the ends of the warps of the supply beam are severally overlapped, in carrying out the invention, in a series of parallel individual channels, and for that purpose the divider is provided and is illustrated in a preferred form. As shown it comprises a base of two separated parts 34 mounted on the support 30 and thus presenting an opening at 35 through the base. This base at the top is slotted transversely and for this purpose the base includes at front and rear separate sections 36, one of which is shown in Fig. 6, with the slots 37 formed therein. A series of thin plates 38 are removably fitted into these slots so that between the plates are formed similar parallel transverse channels open at the top and opening at the bottom through the opening 35 in the base.

In carrying out the method when the running warp beam is exhausted the running warps are severed at a point to leave them extending from and segregated by the separator in the loom. With the supporting frame adjacent the end of the loom, the separator with the projecting segregated ends of the running warps is placed in position on the supporting frame. In the illustration it is assumed that the warps of the upper running beam are to be united to those of the supply beam and in this case the running warps are severed at 39 and the reed 12 is mounted in the supports 29 with the running warps lying over the roller or guide bar 21 and projecting through

the reed. The warp ends 15 extending from the supply beam now mounted on the frame are carried up over the roller or guide bar 32 and the reed 19 of the separator segregating these ends is placed in position on the supports 31 with the ends projecting therethrough. When lease rods are employed they are at the same time in each case positioned between the respective guide bars and reeds.

Next, the ends of the warps on the supply beam and the oppositely facing ends of the running warps are combed into the series of parallel individual channels of the divider so as to cause the ends of the one set to be overlapped individually in regular sequence upon the oppositely facing individual ends of the other set in the said channels. For enabling this operation to be performed efficiently there is provided a hand comb, such as shown in Figs. 2, 3, and 4, comprising a head 40 with depending teeth 41 constructed so that the dents of this comb correspond to the dents of the reeds of the separators. This comb is of comparatively short length so that the warp ends are combed in sections.

25 The operation of laying the warp ends in overlapping relation in the divider may be performed in any desired sequence. Preferably, however, the warp ends of the supply beam are first laid by the comb in the divider and then the ends of the running warps are laid in the divider overlapping the ends from the supply beam. As illustrated in Fig. 2 in carrying out this combing action the comb is inserted by the operator over the segregated ends of the supply beam adjacent the reed 19 and then carried over the divider into the position shown at the left to lay the ends in the individual channels. Then with the comb removed the section of ends thus laid is preferably secured and for that purpose a series of clips 42 are provided on the support 30, one for each section of ends. In the next step the comb is placed over a section of the ends of the running warps adjacent the reed 12 and the comb is moved to the position indicated at the right in Fig. 3 to lay this section of ends in the divider channels overlapping the section first laid. Then the comb is removed, and this section of ends preferably carried over and held by one of the series of clips 43 provided on a bar 44 removably mounted on the supports 33 of the frame.

55 In carrying out this combing operation the ends of the warps of the supply beam are preferably first laid section by section until all ends are positioned in the channels and then the ends of the running warps are likewise laid section by section in the channels until all the ends are laid. As a result, regardless of the sequence of the steps employed, all of the ends are positioned with two overlapping in each channel.

60 Then the overlapping ends are adhesively secured together by applying an adhesive in the channels. For this purpose a rubber latex has been found efficiently and firmly to secure the overlapping ends together. The latex may be dried by projecting warm air on the channels and desirably talcum powder may be sprinkled on the latex.

70 The free portions of the overlapping ends are then preferably severed close to the divider and thus the warps are left continuous from the supply beam to the loom. The separator 19 is then removed from the warps preferably by removing the upper head of the reed, the guide bars 21 and

32 are removed from the supporting frame, and the divider with its support is separated from the warps by removing it from the frame and then, the exhausted running beam having been removed from its gudgeons, the supply beam is placed in position in the loom and the separator, such as 12, restored to its position in the loom.

When lease rods are employed, and consequently there are two dents in a reed, it will be obvious that the sheet of warps may be divided into two parts and each one of these parts successively handled in sections by the combing operation.

The clips provided for holding the compacted ends of the several sections of warps have an important function in that they maintain the warps taut or under slight tension so that when the uniting of the warp ends has been effected the continued warps will run evenly from the supply beam to the loom.

The invention thus provides a very simple and efficient method for securing the continuous operation of the loom by uniting the warps from a supply beam to the running warps in the loom and also a simple and efficient apparatus for carrying out the method.

Having thus described the invention, what is claimed as new and desired to be secured by Letters Patent is:

1. The method of continuing the warps in a loom which consists in inserting the ends of the warps on a supply beam and the oppositely facing ends of the running warps into a series of parallel individual channels to cause the ends of the one set to be overlapped individually in regular sequence upon the oppositely facing individual ends of the other set in said channels, applying an adhesive to each pair of overlapped ends in the channels to effect their adhesion, and separating the adhering ends from the channels.

2. The method of continuing the warps in a loom as defined in claim 1, in which the inserting step is performed by combing the ends into the channels.

3. The method of continuing the warps in a loom as defined in claim 2, in which the combing step is performed upon the said ends section by section.

4. The method of continuing the warps in a loom as defined in claim 3, in which the free ends of each section of the said ends when laid in the channels are clamped to hold the warps taut.

5. The method of continuing the warps in a loom which consists in segregating with a separator the warps extending from the loom segregating with a second separator the ends of the warps on a supply beam, positioning the first separator with its segregated ends extending therefrom adjacent one side of a divider having a series of transverse parallel individual channels, positioning the second separator with its segregated ends adjacent the opposite side of the divider, severally overlapping the ends of the two sheets of warps extending from the respective separators with one pair in each channel, applying an adhesive to each pair of the thus overlapped ends in the channels to effect their adhesion, thereafter separating the divider and the adhering ends, and placing the supply beam in the loom.

6. The method of continuing the warps in a loom as defined in claim 5, in which the step of severally overlapping of the ends of the two sheets of warps extending from the respective separators

positioned at opposite sides of the divider is performed section by section with a comb.

7. The method of continuing the warps in a loom which comprises segregating with a separator comprising a reed the running warps as they enter the loom from the running beam, segregating with a second separator comprising a reed the ends of the warps on a supply beam, severing the running warps between the running beam and the first reed, inserting a comb in a section of the segregated ends of the supply beam adjacent the second reed to position and maintain the segregation of said ends in the comb, moving the comb and contained ends to lay the said section of ends in and maintain their segregation in a corresponding set of a series of parallel individual channels, repeating the preceding pair of steps until all the said ends are positioned in the series of channels, inserting a comb in a section of the segregated ends adjacent the first reed to position and maintain the segregation of said ends in the comb, moving the comb and contained ends to lay the said section of ends in and maintain their segregation in the aforesaid set of channels, repeating the preceding pair of steps until all the said ends are positioned in the series of channels, thereby to cause, regardless of the sequence of the preceding two pairs of steps, all of the ends to be positioned with two overlapping in each channel, applying an adhesive to the overlapped ends in the channels to effect their adhesion, separating from the adhering ends the channels and the second separator and replacing the said running beam with the supply beam to cause the warps to continue segregated by the other reed as they enter the loom.

8. An apparatus for use in uniting two sets of warps comprising a supporting frame, a divider 40 extending transversely of the frame presenting a series of longitudinal parallel individual channels open at the top, a reed for segregating one set of warp ends removably mounted on the frame parallel with and at one side of the divider, and a second reed for segregating the other set of warp ends removably mounted on the frame parallel with and at the other side of the divider.

9. An apparatus for use in uniting two sets of warps comprising a supporting frame, a divider 50 extending transversely of the frame presenting a series of longitudinal parallel individual channels open at the top, a reed for segregating one set of warp ends removably mounted on the frame parallel with and at one side of the divider, a second reed for segregating the other set of warp ends removably mounted on the frame parallel with and at the other side of the divider, and a plurality of clamps on the frame at each side of the divider to hold compacted ends of groups of warps laid from the reed at the opposite side through the channels.

10. An apparatus for use in uniting two sets of warps comprising a supporting frame, a divider 65 extending transversely of the frame presenting a series of longitudinal parallel individual channels open at the top, a reed for segregating one set of warp ends removably mounted on the frame parallel with and at one side of the divider, a second reed for segregating the other set of warp ends removably mounted on the frame parallel with and at the other side of the divider, and a guide bar on the frame for each set of warps located at that side of the reed for its set further from the divider.

11. An apparatus for use in uniting two sets

of warps comprising a supporting frame, a divider extending transversely of the frame presenting a series of longitudinal parallel individual channels open at the top, a reed for segregating one set of warp ends removably mounted on the frame parallel with and at one side of the divider, a second reed for segregating the other set of warp ends removably mounted on the frame parallel with and at the other side of the divider, and means for removably mounting the divider on the frame.

12. An apparatus for use in uniting two sets of warps comprising a supporting frame, a divider extending transversely of the frame presenting a series of longitudinal parallel individual channels open at the top, a reed for segregating one set of warp ends removably mounted on the frame parallel with and at one side of the divider, a second reed for segregating the other set of warp ends removably mounted on the frame parallel with and at the other side of the divider, and supports for the gudgeons of a beam for the one set of warps located on the frame beneath the top of the frame and at that side of the frame at which the reed for the other set of warps is positioned.

10

5

13. A divider for an apparatus for use in uniting two sets of warps comprising a base having an opening therethrough extending longitudinally thereof and having parallel slots in the top extending transversely thereof, and a series of plates removably fitting the slots and forming similar parallel transverse channels open at the top and opening at the bottom through the opening in the base.
